UNITED STATES PATENT OFFICE

170,835

FRYER UNIT OR THE LIKE

Ray C. Sandin, Northbrook, Ill., assignor to General Electric Company, a corporation of New York

Application December 30, 1952, Serial No. 22,918

Term of patent 14 years

(Cl. D81—10)

To all whom it may concern:

Be it known that I, Ray C. Sandin, a citizen of the United States, residing at Northbrook, in the county of Cook and State of Illinois, have invented a new, original, and ornamental Design for a Fryer Unit or the like, of which the following is a specification, reference being had to the accompanying drawings forming a part thereof.

Fig. 1 is a front perspective view of a fryer unit or the like, showing my new design.

Fig. 2 is a side elevation thereof showing the heating elements in rest position.

I claim:

The ornamental design for a fryer unit or the like, substantially as shown.

RAY C. SANDIN.
